BALINT KOVÁCS, OF CASTALIA, OHIO, ASSIGNOR OF ONE-THIRD TO CHARLES K. SABO,
OF CASTALIA, OHIO, AND ONE-THIRD TO ALEX HARI, OF BAYBRIDGE, OHIO

MATCH BOX

Application filed August 16, 1928. Serial No. 300,028.

This invention relates to certain new and useful improvements in match boxes of the pocket type and has for its primary object to provide a match box with a delivery opening therein for a single match and further having a striking or scratching surface in the path of travel of the match head to effect ignition of the match during its withdrawal from the box.

10 A further object of the invention is to provide a match box of the above type in which the initial delivery of the match therefrom is first fully displaced from the container or box with side tapering walls at the delivery 15 end of the box engaging the sides of the match head to prevent complete discharge and to cause said match to be withdrawn laterally with the head thereof contacting a scratching surface to ignite the same at the 20 end of its travel from the box.

With the above and other objects in view that will appear as the nature of the invention is better understood, the same consists in the novel form, combination and arrangement of parts hereinafter more fully described, shown in the accompanying drawing and claimed.

In the drawing:—

Figure 1 is a perspective view of a match box constructed in accordance with the present invention, the same being illustrated as oval in cross-section;

Figure 2 is a side elevational view of the match box showing a match partially withdrawn through the match delivery opening and illustrating by dotted lines, the scratching surface and an ignited match at the point of complete removal from the box;

Figure 3 is an edge elevational view showing the lower edge opening slot with the inclined walls to prevent endwise removal of the match and to necessitate lateral removal thereof;

Figure 4 is a bottom plan view of the box, showing the false bottom with the discharge opening and the scratching face on the lower side of the false bottom;

Figure 5 is a vertical cross-sectional view taken on line 5—5 of Figure 3; and

Figure 6 is a vertical cross-sectional view taken on line 6—6 of Figure 2.

The match box being preferably constructed of relatively thin sheet metal, comprises a body portion 1 oval in cross-section as shown 55 in Figure 1 with the upper end thereof externally reduced in thickness to provide a seating shoulder for the removable slip cover 2, the lower end of the body portion 1 being provided with a false bottom 3 set upwardly 60 from the extreme lower end 4.

A pair of upwardly diverging walls 5 extend between the bottom wall 4 of the body portion and the false bottom 3 parallel with the major horizontal axis of the body portion defining a restricted slotted opening 6 at the extreme lower end of the box body that is open at one end as at 7 with the other end thereof closed as at 8. The false bottom 3 adjacent the closed end 8 of the slot is provided with a match delivery opening 9 while the lower face of the false bottom 3 between the inclined walls 5 is roughened as at 10 to provide a match scratching surface.

The matches M are placed in the box upon 75 removing the cover 2 and a single match is deliverable from the box through the opening 9. The head H of the match is of a diameter greater than the diameter of the slot 6 to prevent complete escape of the match when delivered through the opening 9 and necessitating complete removal thereof through the box by moving the match laterally between the inclined walls 5 and through the slot 6 at the open end 7 thereof. During lateral movement 80 of the match, the head H thereof is moved over the scratching surface 10 for igniting the same as indicated by dotted lines in Figure 2. The match delivered through the bottom opening 9 is shown in Figure 3, while movement thereof over the scratching surface for the purpose of igniting the same is illustrated by dotted lines in Figure 2. As stated, it is necessary to withdraw the match laterally 85 through the slot 6 to effect complete withdrawal thereof from the box and during such movement, the same is ignited.

While there is herein shown and described the preferred embodiment of the invention, it is nevertheless to be understood that minor 90 100

changes may be made therein without departing from the spirit and scope of the invention as claimed.

What I claim as new is:—

- 5 1. In a match box of the character described, a box body and removable cover, a false bottom for the body set upwardly from the lower end and having an opening at one end thereof for the single delivery of a match,
- 10 10 a pair of downwardly converging side walls at opposite sides of the delivery opening and extending between the false bottom and lower end of the box body, and a scratching surface on the bottom face of the false bottom.
- 15 15 2. In a match box of the character described, a box body and removable cover, a false bottom for the body set upwardly from the lower end and having an opening at one end thereof for the single delivery of a match,
- 20 20 a pair of downwardly converging side walls at opposite sides of the delivery opening and extending between the false bottom and lower end of the box body, and a scratching surface on the bottom face of the false bottom,
- 25 25 the lower edges of the side walls and box bottom defining a bottom and an end opening slot with the bottom slot of a diameter less than the diameter of the match head to necessitate withdrawal of the match through the slot end.
- 30 30

In testimony whereof I affix my signature.

BALINT KOVÁCS.
